UNITED STATES PATENT OFFICE.

GEORGE W. MCGILL, OF NEW YORK, N. Y.

DESIGN FOR A METALLIC FASTENER.

SPECIFICATION forming part of Design No. 22,655, dated August 1, 1893.

Application filed July 6, 1893. Serial No. 479,759. Term of patent 14 years.

To all whom it may concern:

Be it known that I, GEORGE W. MCGILL, a citizen of the United States, residing at Riverdale, New York, in the county of New York, State of New York, have invented and produced a new and original Design for Decorative Metallic Fasteners, of which the following is a specification.

This design has for its object to provide a novel and ornamental decorative metallic fastener and consists in a duplex-shanked fastener having a fleur-de-lis shaped head, fashioned on its upper-surface in relief, and extending from its under-surface two superimposed prongs.

The design is illustrated by the accompanying drawings in which--

Figure 1 is a plan view of the top of the fastener partly in perspective and Fig. 2 is an end view of the fastener.

In the drawings the numeral 1 indicates

the fleur-de-lis shaped head, having its upper surface in relief, and numeral 2 the lower surface from the center of which extend two superimposed prongs 3 and 4.

The design provides a novel and ornamental decorative fastener, which presents a striking and characteristic appearance.

What I claim is--

The design for a decorative metallic fastener having a fleur-de-lis shaped head, fashioned on its upper surface in relief, and extending from its under surface two superimposed prongs, substantially as shown and described.

In testimony whereof I have hereunto set my hand and affixed my seal in the presence of two witnesses.

GEORGE W. MCGILL. [L.S.]

Witnesses:

WILLIAM H. HAINS,

JOHN ELTON WAYLAND.
